UNITED STATES PATENT OFFICE

2,426,149

TOOTHPICK DISPENSER

John E. Kenkel, Great Falls, Mont.

Application July 7, 1945, Serial No. 603,606

3 Claims. (Cl. 312—77)

1

This invention relates to a device for dispensing toothpicks and the like, one at a time, and has especial reference to devices disclosed in Patents Nos. 1,428,439, 1,600,886 and 1,962,018, granted to me.

The principal object of the present invention is the provision of a device of the indicated character which is of simplified construction and well suited for economic manufacture from low cost materials.

The nature of the invention and its distinguishing features and advantages will appear when the following specification is read in connection with the accompanying drawing, in which—

Fig. 1 is a front view of a device embodying the features of the invention.

Fig. 2 is a horizontal sectional view taken on the line 2—2 of Fig. 1.

Fig. 3 is a vertical sectional view taken on the line 3—3 of Fig. 1, illustrating the manner in which a toothpick may be grasped to remove it from the device.

Fig. 4 is a fragmentary vertical sectional view of the device showing the relation of the parts as a toothpick is being removed.

Fig. 5 is a view similar to Fig. 4, but showing a continuation of the operation illustrated in Fig. 4.

As shown in the drawing the device of the present invention comprises two main correlated sections consisting of a stationary lower or base section 10 and a movable upper section 11. These sections 10 and 11 may be made entirely of wood or plastic material.

The lower section 10 is adapted to rest on a suitable horizontal supporting surface. Accordingly, the section 10 includes a base 12 consisting of a rectangular block whose upper and lower surfaces are flat and parallel to each other. Uprights 13 are secured to the base block on opposite sides respectively. Vertical rest members 14 are secured to the base 12 on the top surface. These members 14 are extended longitudinally in spaced parallel relation to each other between the opposite sides of the base. The upper edge portion of each member 14 is notched, there being a series of small agitating notches 15 along the rear and V shape notches 16, 17, 18 and 19, respectively, along the remaining portion of the member 14. The notches 16, 17, 18 and 19 provide an arrangement of inclined surfaces as will be understood. These surfaces are varied in length. Some of the surfaces serve as guideways and others serve as abutments for purposes explained hereinafter.

The upper section 11 comprises a box-like struc-

2

ture 30 having a bottom 31, side walls 32, front wall 33, back wall 34 and top wall 35. The bottom 31 slopes slightly forwardly and downwardly. The front wall 33 may include a removable transparent panel, and the top wall 35 also may be a removable transparent panel with both in sliding engagement with the side walls of 32. The top wall 35 serves as a cover held in closed position by suitable means such as the turnable latch 36 on the back wall 34. The bottom 31 has elongated openings 37 therein to accommodate the members 14, respectively, of the base section. By reason of the openings 37 there is provided a central member 38 having V shape notches 39 and 40, top side. These notches provide an arrangement of inclined surfaces. Some of the surfaces serve as guideways and the others as abutments. The notched central member 38 operates between the aforesaid members 14. Also, by reason of the openings 37 the bottom 31 has side extensions 45 to which are attached angle pieces 46, thus providing channels or chutes 47 extending forwardly and downwardly on the front of the structure 30 at opposite sides. The inner ends of the channels 47 communicate with the interior of the structure 30 and the outer or front ends are open. A baffle 48 on the inside of the front wall is disposed transversely so as to restrict the inner ends of the chutes 47 so that only one article or toothpick may pass to the chutes.

The upper section 11 having the above mentioned features is mounted on the lower section 10 for rocking movement with respect thereto on a horizontal axis. Accordingly, suitable pivots 49 carried by the uprights 13, respectively, extend into the side walls 32.

The box-like structure 30 serves as a magazine for the articles to be dispensed. Toothpicks 50 are shown by way of example. The latch 36 may be turned to a position to enable the panel 35 to be removed for the introduction of a supply of the toothpicks within the magazine.

The upper section 11 normally is disposed under the action of gravity in a forwardly and downwardly inclined position, as shown in Fig. 3. Repeated up and down movement of the section 11 puts one toothpick across the members 14 with the opposite end portions of the toothpick disposed in the notches 18 and adjacent chutes 47, respectively. This particular toothpick is designated T. It may be grasped between the forefinger and thumb of one hand and be withdrawn, thereby causing the section 11 to rock upwardly, due to the fact that the end por-

tions of the toothpick T are caused to perform a wiping action on the pieces 46 as indicated in Figs. 4 and 5. In Fig. 4 the section 11 is partly up and in Fig. 5 the section 11 is all of the way up, enabling the toothpick to be removed from the open ends of the chutes 47. As the section 11 is rocked upwardly to remove a toothpick and is then allowed to rock downwardly another toothpick is transferred to the pair of notches 18. The repeated up and down rocking movement of the section 11 causes one toothpick at a time to be advanced to the notches 18. Each toothpick advances from the notches 16 into and out of the notches 39, 17, 40, and then into the notches 18 in the order mentioned. The notches 39 and 40 are staggered with respect to the notches 17 and 18 for the purpose mentioned.

The notches 19 are not necessary for the proper operation of the device. The notches 19 are provided to prevent playful children and foolish adults from rocking the section 11 without removing a toothpick and so filling the notches 18. Should the section 11 be rocked upwardly without removing the toothpick from the notches 18 it will be lifted into the notches 19, as indicated by the toothpick designated T' in Fig. 4. The toothpick T' in the notches 19 will prevent the section 11 from rocking downwardly due to the fact that the parts 46 will strike the end portions of the toothpick T'. By removing the toothpick T' another toothpick will be delivered into the notches 18 for the proper and orderly operation of the device.

It is to be understood the invention is not restricted to the showing in the drawings, but that details of construction may be modified and rearranged in accordance with the appended claims.

I claim:

1. A toothpick dispenser comprising a stationary base section adapted to rest on a suitable horizontal support, an upper magazine section for a supply of toothpicks mounted on the base section for pivotal movement on a horizontal axis, forwardly and downwardly inclined and

laterally spaced cooperative delivery chutes channel shape in cross section connected with the magazine section at opposite sides thereof, said chutes communicating with the interior of the magazine section in such manner that only one toothpick at a time may pass out of the magazine section with its opposite end portions disposed in said chutes, spaced upright stationary members on the base section extending in a front to back direction between the chutes, said magazine section having a bottom with elongated openings therein into which said stationary members project so that the bottom is movable with respect thereto in the pivotal movement of the magazine section, the stationary members and said bottom having an arrangement of inclined surfaces and abutments to advance said toothpicks step by step one at a time out of the magazine section with the end portions disposed in said chutes as the magazine section is caused to pivot up and down by reason of the withdrawal from the chutes of the most advanced toothpick by grasping the toothpick between its ends.

2. A toothpick dispenser as set forth in claim 1, wherein the inclined surfaces and abutments of the stationary members are staggered with respect to those of the bottom.

3. A toothpick dispenser as set forth in claim 1, wherein the stationary members have notches which may receive a toothpick disposed with its end portions in said chutes to prevent the downward pivotal movement of the magazine section until said toothpick is removed.
